(57) CLAIM

We claim the ornamental design for case for a tablet shaped device, as shown and described.

DESCRIPTION

FIG. 1 is a front bottom perspective view of a case for a tablet shaped device.

FIG. 2 is another side front bottom perspective view of a case for a tablet shaped device.

FIG. 3 is a rear bottom view of the case for a tablet shaped device.

FIG. 4 is a top view of the case for a tablet shaped device.

FIG. 5 is a rear view of the case for a tablet shaped device.

FIG. 6 is a left side view of the case for a tablet shaped device.

FIG. 7 is a front bottom perspective view of the case for a tablet shaped device; and,

FIG. 8 is a front bottom perspective view of the case for a tablet shaped device.

The portions of the figures shown in dashed lines are not part of the claimed invention.
